[57] CLAIM

The ornamental design for an identification clip, as shown and described.

DESCRIPTION

FIG. 1 is a front elevational view of an identification clip, showing our new design, with the broken line showing for illustrative purposes only and forming no part of the claimed design;

FIG. 2 is a right hand side elevational view, wherein the left hand side elevational view is substantially identical;

FIG. 3 is a bottom plan view;

FIG. 4 is a cross-sectional view, taken along the line IV-IV, FIG. 1;

FIG. 5 is a rear elevational view; and,

FIG. 6 is a perspective view thereof.
